UNITED STATES PATENT OFFICE.

EDUARD LEISSNER, OF NEW YORK, N. Y.

DESIGN FOR WALL-PAPER.

SPECIFICATION forming part of Design No. 13,152, dated August 8, 1882.

Application filed June 30, 1882. Term of patent 3½ years.

To all whom it may concern:

Be it known that I, EDUARD LEISSNER, of New York, in the county and State of New York, have invented a new and original Design for Wall-Paper and Similar Fabrics, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

B is a stripe containing an ornamentation consisting of figures *a*, which is a cluster of

circular indented leaves, and of clusters *f* of circular indented flowers of the shape of pansies. These clusters of leaves *a* and the flowers *f* are set upon the stems, and alternate with each other to make up the ornamentation of 20 the stripe B.

I claim—

The design for wall-paper, consisting of the stripe B, containing figures *a* and *f*, substantially as shown.

EDUARD LEISSNER.
